METHOD AND APPARATUS FOR LINING
CROWN CAPS

Paul E. Pearson, Chicago, Ill., assignor to Continental Can Company, Inc., New York, N. Y., a corporation of New York

Application July 12, 1937, Serial No. 153,245

41 Claims. (Cl. 113—80).

The invention relates generally to the assembling of container closure caps of the crown type, each including a metallic cap having a skirt adapted to fit over and grip the pouring neck of a can, bottle, or other container and a sealing pad of cork or other suitable yieldable material for engaging said neck and effectively sealing the contents of the container, and said invention primarily seeks to provide a novel method of and apparatus for affixing protective disks to the pads in such caps.

Closure caps designed for use on containers for beer or similar beverages usually have the sealing pads thereof faced with an impervious liner disk of aluminum or other foil or treated paper so as to prevent direct contact between the beverage and the pad and also to prevent leakage of gases. It has been found advantageous to employ facing disks of the "center spot" type, that is to say disks of a diameter less than that of the pad so as to protect the beverage from pad contact and yet permit contact between the container neck and an annulus of pad surface so as to provide the most effective seal possible. The affixing of lining disks to cap pads, particularly disks of the "center spot" type, has presented numerous problems. Probably the most effective manner of affixing the disks has been by use of a heat fusible adhesive, that is to say an adhesive normally non-tacky but rendered tacky by application of heat. Even the manner of applying the necessary heat has presented problems difficult of solution.

Some workers in the art have applied heat to the metallic caps but this has been found to be injurious to the decorated and printed surfaces of the caps. Others have sought to heat the pads within the caps and have been confronted with the problem of scorching the pads and impairing their sealing qualities or burning and entirely ruining them. Even when partially successful such efforts have been only indirectly effective for the intended purpose of heating the fusible cement carried by the disk material and have served to complicate and unduly encumber the apparatus necessary to be used. Such methods and apparatus, however, had one redeeming feature in that they made possible the use of cold punches for cutting out or forming the liner disks, and such punches presented no troublesome problems with respect to expansion and contraction of metals.

Other workers in the art, seeking to avoid the disadvantages of preheating the caps, have sought to use hot plungers and have experienced

problems of metal expansion and contraction, and some have used cold plungers for cutting the liner disks in conjunction with subsequently operative, complicated, heated setting plunger equipments.

It is to the elimination of the problems and disadvantages above enumerated that I have addressed my efforts.

Among the objects of the invention is to provide a novel method of applying cap liner disks which comprises the steps of forming and directly attaching a fusible adhesive coated liner disk to a holding device, heating the disk while held by the holding device, applying the disk to a sealing pad by use of the holding device, and applying pressure to cause the disk to permanently adhere to said pad.

Another object of the invention is to provide a method including the step of applying the "spot" to the pad by a movement in a direction opposite the direction of movement which effects the punching out of the "spot".

Another object of the invention is to provide a novel method of applying cap liner disks which includes the step of directly heating the liner disk to fuse or render tacky its adhesive coating.

Another object of the invention is to provide a novel method of assembling a "spotted" crown cap which comprises the steps of punching a "spot" from a strip of fusible adhesive coated spotting material by use of a cold punch, pneumatically and directly attaching the "spot" to a holding plunger, heating the adhesive coated surface of the "spot" while it is supported on the plunger, bringing about a centered relation between a pad equipped cap and said "spot", and utilizing said plunger to apply and secure the "spot" centrally on said pad.

Another object of the invention is to provide novel apparatus for carrying out the novel method steps above enumerated in a manner assuring constant control of the formed disks and eliminating all possibility of disruption of the centered relation of said disks.

Another object of the invention is to provide a novel "spotted" crown cap assembling machine in which is provided padded cap feeding means, a step-by-step rotatable table or rotor having multiple faces each equipped with a plurality of cap receiving pockets, means to present the table faces serially through successive station positions at one of which pad equipped caps are fed into the receiving pockets and cold plungers punch out a plurality of "spots" from a strip of fusible adhesive coated material after

which said "spots" are affixed to carrying plungers, at succeeding stations of which said carried "spots" are heated, at successive stations of which said plungers apply the heated spots to the cap pads and exert a pressure thereagainst for permanently attaching said "spots", and at another station of which the assembled caps are discharged.

Another object of the invention is to provide an apparatus of the character stated embodying a novel means for punch forming the "spots" including devices for so positioning the spotting material that it is punched through from its adhesive coated side.

Another object of the invention is to provide a novel means for controlling the functions of the cap feeding means, the punching means, the spot material feeding means, the "spot" affixing and applying means, the heating means, and the cap delivering means.

With the above and other objects in view that will hereinafter appear, the nature of the invention will be more fully understood by following the description, the appended claims, and the several views illustrated in the accompanying drawings.

In the drawings:

Figure 1 is a plan view of a machine embodying the invention, parts being broken away and in section;

Figure 2 is a side elevation of the machine, parts being broken away and in section;

Figure 3 is a rear end elevation of the machine;

Figure 4 is a horizontal section taken on the line 4—4 on Figure 2;

Figure 5 is an enlarged vertical cross section of the table taken on the line 5—5 on Figure 1;

Figure 6 is an enlarged detail plan and part horizontal sectional view of a segment of the intermittently movable table and the punch and die equipments in operative position;

Figure 7 is a fragmentary, somewhat diagrammatic plan and part horizontal sectional view illustrating the retracted condition of the punch and die equipments;

Figure 8 is a detail vertical cross section taken on the line 8—8 on Figure 7;

Figure 9 is a diagrammatic plan view illustrating the paths of movement followed by the carrier or holder and cap discharging slide roller axes respectively;

Figure 10 is a detail vertical section taken at station one and showing the method steps of punch-forming the liner disks and affixing them to the holders or carriers;

Figure 11 is a detail vertical section taken at station two and showing the method step of directly heating the liner disks;

Figures 12 and 13 are detail vertical sections taken just in advance of station six and showing the method steps of first retracting the carriers or holders to allow a cap to fall into centered position and then projecting the plunger to apply the liner disk to the cap pad and hold it firmly thereagainst;

Figure 14 is a detail vertical section taken at station eight and showing the method step of discharging the assembled caps;

Figure 15 is a detail vertical section illustrating the stripping of the spots from the punches;

Figure 16 is a diagrammatic plan illustrating the paths of movement followed by the carrier or holder and cap discharging slide roller axes respectively in practicing the method modification shown in Figure 17;

Figure 17 is a view similar to Figure 10 and showing a modified method step in which the forming or cutting of the liner disks is accomplished by the carriers or holders; and

Figures 18 and 19 are plan and vertical cross sectional views illustrating a "spotted" crown cap.

In the drawings in which like numerals of reference indicate like parts in all of the figures, the apparatus selected as an example embodiment of the principles of the invention includes a frame having a base standard 5 and a rotor shell portion 6 supported thereon.

A bearing shaft or column 7 is rigidly secured to the frame and projects vertically therefrom, as shown in Figure 2. The column 7 includes a bearing portion 8 about which the hub 9 of a rotor or turret 10 is freely rotatable. The rotor includes an octagonal peripheral flange 11 providing eight station faces or sectors and is adapted to be indexed about the center column to present its faces serially in a manner, and for a purpose, soon to be described.

To provide for proper indexing of the rotor, said rotor is equipped with a plurality of rollers 12, one depending centrally beneath each rotor sector as shown in Figures 2 and 4. These rollers are engaged and moved step-by-step by the flanges 13 of the groove cam 14 carried by the shaft 15 having horizontal transverse bearing as 16 in the frame portion 5. Such rotor indexing cams are well known and serve at each revolution to advance or index the table one station and then hold it stationary during a definite dwell period. A worm wheel 17 is secured to the shaft 15 and is driven by a worm 18 carried on a drive shaft 19 to which power is applied through pulleys 20, or other suitable power transmitting devices, from a suitable power source, under control of a clutch 21 and control lever 22. Indexing of the rotor can be effected also by a hand wheel 23 whenever desired.

At each sector the rotor is equipped with a T-shaped slideway 24 and a ceiling piece 25 covering only the outer portion of said slideway. A face plate 26 is removably secured, as at 27, to the peripheral face of the rotor flange 11 at each sector, and is equipped with a battery (five in this illustration) of vertically disposed cap receiving grooveways 28. Each plate 26 and its associated rotor flange portion is equipped with a battery of horizontal bores 29, each said bore passing centrally through one of the grooveways 28.

Extending across beneath each battery of grooveways, is a rotor bottom opening 30 through which caps may be discharged from the grooveways 28. Each such opening is normally closed by the T-head portion of a slide 31. The sides of the grooveways 28 and the top surface of each slide 31 are so spaced with relation to the respective bores 29 that the crown caps, when received in the grooveways as shown in Figure 12, are centered across said bores.

A second T-head slide 32 is slidable over the T-head slide 31 at each rotor sector and carries a battery of pneumatic holders or carriers 33 slidable in the bores 29. In this particular illustration, the carrier or holder elements are in the nature of suction plungers.

A grooved plate cam 34 is stationarily mounted, as at 35, on the column 7. The cam includes a track groove 36 for receiving a roller 37 projecting upwardly from each cap discharge control slide 31, and a track groove 38 for receiving a roller 39 projecting upwardly from each carrier 33.

or holder element slide 32. It will be readily understood that as the rotor is moved step-by-step about the column 7, the rollers 37 and 39 will be moved along in the cam grooveways 36 and 38, and the grooveways will determine the positions of the slides. The path of movement followed by the respective rollers 37, 39 is illustrated by the dot and dash lines in Figure 9.

Each holder or carrier 33 is provided with an axially disposed suction duct 40. All of the ducts of each battery of plungers communicate with a manifold duct in the slide head which carries them, and each manifold duct communicates, through a pipe line 41 including a flexible section 42, with a valve member 43 rotatable about a tapered hub 44 secured at 45 upon the column 7. The valve member 43 is held against endwise movement by a keeper head 46 secured on the hub 44. The valve member 43 is caused to move with the table 16 by radial arms 47 secured at their inner ends to said member, and at their outer ends, by pin and slot connections 48, to the ceiling pieces 25 of the table. An annular suction duct 49 is provided in the valve member 43 and is connected with the several pipe lines 41 and with a single pipe line 50 leading to a suitable exhauster or source of negative pressure (not shown).

A bracket member 51 is secured, as at 52, to the base at the position at which the sealing pad equipped crown caps are fed to the rotor grooveways or pockets. For convenience of description this position is referred to as station (#1) and each stop station succeeding this station will be individually identified, as stations (#2), (#3), etc., up to and including station (#8) which is the cap discharging station. The functions taking place at the several stations will be described in detail hereinafter.

The bracket 51 carries a pair of slide guide members 53, removably secured thereon as at 54, and grooved to receive and guide a slide member 55. A shaft 56 is rockably supported on the bracket and a crank member 57 is secured on the shaft and link-connected as at 58 with the slide member 55. Another crank member 59 is secured on the shaft 56 and connected by a thrust arm or pitman 60 with a strap member 61 encircling an eccentric 62 carried by the shaft 15 hereinbefore referred to. The rotary motion of the shaft 15 is transmitted to the slide member 55, in the form of reciprocating motion, by the connections, 62, 61, 60, 59, 58, 57 and 56.

A battery of punches 63, corresponding in number and axially aligned with the bores 29 in the rotor face presented in opposition therewith at any given time, projects longitudinally from the slide member 55, being removably and adjustably secured thereon as at 64. The slide member 55 includes a pair of guide bores 65 equipped with slide rods 66. The rods are free to project through the opposite ends of the bores and are frictionally held in said bores by friction pins 67. See Figures 6, 7, and 8. At the ends thereof presented toward the periphery of the rotor, the rods 66 carry a die member 68, removably secured thereon as at 69. A die plate 70 is removably secured, as at 71, in a face recess formed in the die member. The face recess is grooved to provide strip receiving grooveways 12 centered on the axes of the punches and a slight bit wider than the diameter of said punches, and bores 73 are formed in the members 68 and 70 to receive the punches, the bores in the plate 70 providing cutting edges for cooperating with the

punches in the formation of spot disks. Adjustable abutments 74 are mounted on the bracket in position for engaging the outer ends of the rods 66 for a purpose that will soon be described.

The bracket member 51 also has provision for supporting five rolls 75 of fusible-adhesive coated-material in strip form. While any suitable spot material can be used aluminum foil is preferred. After leaving the rolls 75 the foil strips 76 pass over guide rolls 77 mounted on and movable with the die member 68, thence through the grooveways 12, thence between feed rolls 78 one of which has a ratchet wheel 79 attached thereto. An oscillatable ratchet arm 80, link driven as at 81 from a crank disk 82 carried by the shaft 15, imparts step-by-step feed movement to the feed rolls. The waste strips fed through the rolls 78 pass over suitable guide rolls to take up spools 83 which rest upon and are driven frictionally by rolls 84 to which rotation is imparted, as at 85, from the shaft 15.

A crown cap supply hopper 86 of any approved type is mounted, as at 87, upon the machine frame and delivers the sealing pad equipped crown caps, through suitable feeder grooveways, 23 into five vertical delivery chutes 88 positioned as shown in Figures 2 and 3 so that their delivery ends 89 align with the cap receiving grooveways 28 of whichever rotor face happens to be presented at station (#1) at the delivery interval.

It will be observed by reference to Figure 9 that the groove 38 of the stationary cam 34 has a portion effective, as the rotor approaches station (#1), to cause the particular roller to move outwardly as indicated at 90, moving the plungers 33 to the position shown in Figure 10, and a portion effective, as the rotor leaves station (#1), to cause said roller to again move outwardly as indicated at 91, moving the plungers to the position shown in Figure 11. While a given rotor sector is located at station (#1), a supply of crown caps are fed to its receiving grooveways 28, and a proper number of liner disks or spots 92 are formed by the punches 63 and transferred by them directly to the holders or carriers 33 whereon they become pneumatically affixed.

In the formation and pneumatic affixing of the spots, at station (#1), the suction plungers are positioned as shown in Figure 10, traversing the cap grooveways 28 and supporting the caps on the upper surfaces thereof. As the rotor sector first moves to this position, the die and punch equipments are positioned somewhat as shown in Figure 7, inactive and spaced from the rotor periphery. During this rest position of the rotor, however, the punch forming equipments actively function. The slide 55, the rods 66 and the die member 68 move as one until the die member engages the rotor face. The die member then remains stationary while the slide 55 moves along the rods 66 and the punches 63 pass through the bores 73, forming spots 92 and transferring them to the pneumatic holders or carriers 33 as above stated.

It will be observed, by reference to Figures 6, 7, and 15, that as the punch and die equipments are withdrawn they move in unison until the rods strike the abutments 74, when movement of the rods 66 will be stopped so that continued movement of the slide 55 will restore the parts to the normal position shown in Figure 7. The relation and operation of parts just described provides not only for the relative movements of the die and punch equipments necessary to form the desired liner disks or spots, but also for the clear-

ances necessary to permit indexing of the rotor. The punches 63 preferably are equipped with axially disposed spring pressed stripper pins 93 which are effective, upon withdrawal of the punches, to strip the spots 93 from the punches should they tend to adhere. It will be noted that these pins are larger in diameter than the suction ducts 40 so as to definitely assure against breakage of suction should edge portions of the 10 spot tend to cling to the punch.

A heating element carrier 94, equipped with a resistance heating element 95 to which electrical energy may be applied as at 96, is supported on a spider 97 attached to a center shaft 98 vertically reciprocable in a bore 99 formed in the center column 7. The carrier surrounds a portion of the rotor, at stations (#2), (#3), (#4), and (#5), being spaced from the peripheral flange thereof as shown in Figures 1, 2, and 11. At its 15 lower end the center shaft 98 is supported on toggle links 100 connected at 101 to a downward extension 102 of the clutch lever 22. Whenever the lever is shifted to throw out the clutch and discontinue movement of the table, the toggle is 20 straightened as shown in Figure 2 and the heating element is lifted to an ineffective position. See Figure 2. By this means it is impossible to subject the pneumatically held liner disks or spots to an abnormal heating interval.

30 As has been previously stated, as a given rotor sector moves away from station (#1) its spot bearing suction plungers 33 are projected to the position shown in Figure 11. In this position the spots 92 are held presented toward the heating 35 element 95 and have heat applied directly to the exposed heat fusible adhesive coated surfaces thereof. The groove 38 of the cam 34 includes a dwell portion, as will be observed by reference to Figure 9, which is effective to hold the carriers 33 in the projected position throughout all of stations (#2), (#3), (#4), and (#5) and the travel intervals intervening said stations. The carriers and the pneumatically held spots thus pass 40 through a heating zone of considerable length.

45 When a given rotor sector is passing from station (#5) to (#6), a portion of the cam groove 38 becomes effective to first withdraw the plungers 33, as indicated at 103 in Figure 9, removing the support from beneath the caps in the groove- 50 ways 28 and permitting them to fall, as shown in Figure 12, into position centered with respect to the plungers, and then again project the carriers or holders, as indicated at 104 in Figure 9, to press the heated spots against the cap pads as 55 shown in Figure 13. A second dwell portion in the cam groove 38 serves to hold the plungers in the position shown in Figure 12 at station (#6), while passing to station (#7), and for an interval after they leave station (#7), permanently setting the spots and completing the assembly of the 60 caps. See 105 in Figure 9.

As a given rotor sector is moving into station (#8), a portion of the cam groove 36 becomes effective as indicated at 106, to withdraw the discharge slide 31 and open the discharge passage 30 through the bottom of the rotor sector. At the same time a portion of the cam groove 38 becomes effective, as indicated at 107, to withdraw the plungers 33 a distance sufficient to free the caps and permit them to fall through the discharge opening, as shown in Figure 14. After the discharge of the assembled caps has been effected at station (#8), and as the rotor sector leaves that station to return again to station 70 (#1), the cam groove 36 becomes effective as in-

5 dicated at 106 in Figure 9, and the cam groove 38 becomes effective as previously stated and as indicated at 90 in the same figure, to restore the slide 31 and the elements 33 to the initial positions shown in Figure 11.

The crank member 59 carries an upward extension 108 engageable with one end of a rod 109 slidably supported at 110 on the bracket 51 and connected at its other end with a crank 111 mounted on a rock shaft 112 which carries a 10 battery of cap holding and releasing fingers 113. The fingers 113 are oscillatable into and out of engagement with the lowermost caps in the feed chutes 88 and the parts are so constructed and arranged that each time a rotor sector moves into 15 position at station (#1) the fingers will be moved away to release the lowermost caps in the chutes 88 and permit them to fall into the rotor flange grooveways 28 on top of the plungers 33 traversing said grooveways. See Figures 2 and 11. 20

In Figure 17 I have shown a modified form of the invention in which the elements 33^a serve the triple function of punch-forming, carrying and applying the spots. In this figure, parts corresponding in construction and function with 25 like parts hereinbefore described are given the same reference numeral with the modification exponent "a".

In order to adapt the apparatus to this modified use, the cam groove 38 is provided with a portion 30 effective, as indicated at 114 in Figure 16, during movement of a given rotor sector to station (#1) to project the plungers 33^a an additional distance to the position shown in Figure 17.

With the plungers 33^a thus positioned, as the 35 slide 55^a moves the die member 68^a and plate 70^a against the rotor face the elements 33^a will act as punches as shown in Figure 17, suitably cutting spots 92^a from the foil strip 76^a. Instead of carrying punches, the slide 55^a carries a battery 40 of spring pressed stripper plungers 115. In this form the cam groove 38 may or may not be equipped with a portion effective during movement of the rotor sectors away from station (#1) to retract the elements 33^a slightly, as indicated 45 at 116 in Figure 16, so that they will not project too closely to the heating element. Aside from these changes the parts function as hereinbefore described.

The method steps will be well understood by 50 reference to Figures 11 through 15 and 17. The liner disks or spots are punch-formed and directly applied to the carrier or pneumatic holders or carriers. By directly affixing the spots as hereinbefore described the spots always are under 55 perfect control and the centered relation of spot, plunger and cap pad can never be disturbed or disrupted. The pneumatic holders or carriers carry the spots through a heated zone where heat is applied directly to the exposed heat fusible adhesive coated surfaces thereof, and then the holders or carriers are pressed against the cap pads for an interval of time suitable for permanently setting the applied spots. 60

The apparatus herein disclosed embodies many novel and advantageous features particularly pointed out in the appended claims, and many of these features may be structurally varied without departing from the scope of the appended 70 claims. It is to be understood also that the apparatus herein disclosed is but an example of apparatus adapted to the practicing of the method steps herein described and claimed as novel, and that other forms of apparatus may be em- 75

ployed in practicing the method without departing from the scope of the appended claims.

I claim:

1. The method of assembling cap pads and protective disks which comprises, pneumatically attaching a fusible adhesive coated disk to a supporting element, heating the disk on said element, and bringing about relative movement between the disk and a pad for applying the disk 10 to the pad.

2. The method of assembling cap pads and protective disks which comprises, pneumatically attaching a fusible adhesive coated disk to a supporting element, heating the disk on said 15 element, bringing about relative movement between the element and a pad for applying the disk to the pad, and thereafter utilizing said element in applying pressure to said disk for permanently uniting it with said pad.

3. The method of assembling cap pads and protective disks which comprises, cold-punching a disk from fusible adhesive coated material by punching through from the coated side of said material, applying heat directly to the coated 25 side of the disk to fuse the adhesive thereon, and affixing the adhesive bearing surface of the disk to a pad.

4. The method of assembling cap pads and protective disks which comprises, cold-punching 30 a disk from fusible adhesive coated material, moving the disk to and pneumatically attaching it with a carrying element, moving said element through a heated zone to fuse the adhesive coating on the disk, and affixing said disk to a pad 35 by pressure applied in part by said element.

5. The method of assembling sealing pad equipped caps and center spots which comprises, cold-punching a spot from fusible adhesive coated material, transferring the spot directly to and 40 affixing it to a pneumatic carrier element, applying heat directly to the adhesive bearing surface of the spot while on said element, positioning a cap and the element with the element in centered relation to said cap, and pressing the element and cap pad to adhesively unite the spot and pad.

6. In a pad and protective disk assembling machine, a disk carrier, means for attaching a fusible adhesive coated disk to said carrier, means 50 for directly heating the disk while on said carrier, means for presenting a pad and said supported disk in centered relation, and means for pressing together the carried disk and a pad to cause the disk to be adhesively united to the pad.

7. In a pad and spot assembling machine, means for punch-forming a spot, pad positioning means, and means for affixing the punch engaged face of the spot to a pad.

8. In a pad and spot assembling machine, 60 means for punch-forming a spot from adhesively coated material with the punch passing through from the adhesive coated side of said material, and means for adhesively uniting the spot and a pad by affixing the adhesively coated face of the 65 spot to said pad.

9. In a pad and protective disk assembling machine, a carrier, punch and die means for punch-forming a disk from heat fusible adhesive coated material and pressing it against said carrier, 70 means for pneumatically attaching the disk to said carrier, pad positioning means, means for heating said disk while on said carrier, and means for pressing the carrier and pad together to adhesively unite the disk and pad.

10. In a pad and protective disk assembling

machine, a pneumatic carrier, means for punching a disk from disk material and presenting it for attachment to said carrier, means for positioning a pad, and means for pressing the carrier and pad together to cause the disk to be united 5 thereto.

11. In a pad and protective disk assembling machine, a pneumatic carrier, means for punching a disk from fusible adhesive coated material and presenting it for attachment to said carrier, 10 means for heating the disk while on said carrier, means for positioning a pad, and means for pressing the carrier and pad together to adhesively unite said pad and disk.

12. In a pad and protective disk assembling 15 machine, a pneumatic carrier, means for punching a disk from fusible adhesive coated material and presenting it for attachment to said carrier, means for moving the carrier through a heated zone to fuse the adhesive on the disk carried 20 thereon by application of heat directly to said adhesive, means for positioning a pad, and means for pressing the carrier and pad together to adhesively unite said pad and disk.

13. In a pad and spot assembling machine, a 25 rotor having a pad feeding and positioning guideway therein and a plunger bore centrally traversing said guideway, a movable slide normally closing the guideway and disposed to center a pad on the axis of the bore, and a spot-apply- 30 ing suction plunger reciprocable in the bore.

14. In a pad and spot assembling machine, a 35 rotor having a pad feeding and positioning guideway therein and a plunger bore centrally traversing said guideway, a movable slide normally closing the guideway and disposed to center a pad on the axis of the bore, a suction plunger reciprocable in said bore, means for applying a spot to said plunger for pneumatic attachment thereto, and means for withdrawing the plunger into 40 the bore to permit a pad to feed into centered relation against the slide and for then pressing the plunger against the pad for uniting the spot therewith.

15. In a pad and spot assembling machine, a 45 rotor having a pad feeding and positioning guideway therein and a plunger bore centrally traversing said guideway, a movable slide normally closing the guideway and disposed to center a pad on the axis of the bore, a suction plunger reciprocable in said bore, means for applying a fusible adhesive coated spot to said plunger for pneumatic attachment thereto, means for heating the spot while on said plunger, and means for withdrawing the plunger into the bore to permit a pad 50 to feed into centered relation against the slide and for then pressing the plunger against the pad for uniting the spot therewith.

16. In a pad and spot assembling machine, a 55 rotor having a pad feeding and positioning guideway therein and a plunger bore centrally traversing said guideway, a movable slide normally closing the guideway and disposed to center a pad on the axis of the bore, a suction plunger reciprocable in said bore, means for applying a fusible 60 adhesive coated spot to said plunger for pneumatic attachment thereto, heating means, and means for first projecting the plunger from the bore to present the spot to the heating means for direct application of heat thereto, for then withdrawing the plunger into the bore to permit a 65 pad to feed into centered relation against the slide, and for then pressing the plunger against the pad for uniting the spot therewith.

17. In a pad and spot assembling machine, a 75

rotor having a pad feeding and positioning guideway, a movable slide normally closing the guideway and disposed to center a pad on the axis of the bore, a suction plunger reciprocable in said bore, means for applying a fusible adhesive coated spot to said plunger for pneumatic attachment thereto, heating means, and means for first projecting the plunger from the bore to present the spot to the heating means for direct application of heat thereto, for then withdrawing the plunger into the bore to permit a pad to feed into centered relation against the slide, for then pressing the plunger against the pad for uniting the spot therewith, and for thereafter again withdrawing the plunger and the slide to permit the spotted pad to feed out of the guideway.

18. In a pad and spot assembling machine, a rotor having a pad feeding and positioning guideway therein and a plunger bore centrally traversing said guideway, a movable slide normally closing the guideway and disposed to center a pad on the axis of the bore, a suction plunger reciprocable in said bore, means for feeding a strip of fusible adhesive coated spot material, means for punching a spot from the strip and applying it to said plunger for pneumatic attachment thereto, heating means, and means for first projecting the plunger from the bore to present the spot to the heating means for direct application of heat thereto, for then withdrawing the plunger into the bore to permit a pad to feed into centered relation against the slide, and for then pressing the plunger against the pad for uniting the spot therewith.

35 19. In a pad and protective disk assembling machine, a suction plunger, means including a punch element reciprocable in axial alignment with said plunger for punching a disk from disk material and presenting it for attachment to said plunger, means for positioning a pad, and means for pressing the plunger and pad together to cause the disk to be united thereto.

20. In a pad and protective disk assembling machine, a suction plunger, means including a punch element reciprocable in axial alignment with said plunger for punching a disk from fusible adhesive coated material and presenting it for attachment to said plunger, means for heating the disk while on said plunger, means for positioning a pad, and means for pressing the plunger and pad together to adhesively unite said pad and disk.

21. In a pad and spot assembling machine, a rotor having a pad feeding and positioning guideway therein and a plunger bore centrally traversing said guideway, a movable slide normally closing the guideway and disposed to center a pad on the axis of the bore, a suction plunger reciprocable in said bore, means including a punch element reciprocable in axial alignment with said plunger for punching a spot from fusible adhesive coated spot material and applying it to said plunger for pneumatic attachment thereto, means for heating the spot while on said plunger, and means for withdrawing the plunger into the bore to permit a pad to feed into centered relation against the slide and for then pressing the plunger against the pad for uniting the spot therewith.

70 22. A pad and spot assembling machine comprising a rotor having a plurality of faces each equipped with a set of pad feeding guideways therein and a set of plunger bores each centrally traversing one of the guideways, slide means normally closing the guideways of each set and dis-

posed to center pads on the axes of the bores of the respective set, a set of suction plungers reciprocable in each set of bores, means for moving the rotor step-by-step to serially present the faces thereof, means for serially applying to the sets of plungers thus serially presented sets of fusible adhesive coated spots for pneumatic attachment to said plungers, heating means disposed adjacent the periphery of the rotor, means for projecting the sets of plungers beyond the rotor periphery during a portion of the rotor travel to present the attached spots to the heating means, means for at a place subsequently reached withdrawing the plunger sets serially into their bores to permit the sets of pads to feed into centered relation against the slides and for then pressing the plunger sets against the pads and holding them there during a travel interval of the rotor to adhesively unite said pads and spots, and means for thereafter serially moving the slides to discharge the assembled pads.

23. A pad and spot assembling machine comprising a rotor having a plurality of faces each equipped with a set of pad feeding guideways therein and a set of plunger bores each centrally traversing one of the guideways, slide means normally closing the guideways of each set and disposed to center pads on the axes of the bores of the respective set, a set of suction plungers reciprocable in each set of bores, means for moving the rotor step-by-step to serially present the faces thereof, means for serially applying to the sets of plungers thus serially presented sets of fusible adhesive coated spots for pneumatic attachment to said plungers, heating means disposed adjacent the periphery of the rotor, and a single cam means for projecting the sets of plungers beyond the rotor periphery during a portion of the rotor travel to present the attached spots to the heating means for at a place subsequently reached withdrawing the plunger sets serially into their bores to permit the sets of pads to feed into centered relation against the slides and for then pressing the plunger sets against the pads and holding them there during a travel interval of the rotor to adhesively unite said pads and spots, and for thereafter serially moving the slides to discharge the assembled pads.

24. In a machine of the character described, a rotor, pad supporting and spot applying means including spot carrying plungers, heating means disposed adjacent the periphery of the rotor, and means for moving the rotor step-by-step to present the plungers and spots carried thereon to the heating means.

25. In a machine of the character described, a step-by-step rotatable rotor, pad supporting and spot applying means including spot carrying plungers, heating means disposed adjacent the periphery of the rotor, means for projecting the plungers at the periphery of the rotor to present the spots to the heating means, and means for rendering the heating means ineffective whenever the step-by-step movement of the rotor is discontinued.

26. In a machine of the character described, a step-by-step rotatable rotor, pad supporting and spot applying means including spot carrying plungers, heating means disposed adjacent the periphery of the rotor, means for projecting the plungers at the periphery of the rotor to present the spots to the heating means, and means for moving the heating means away from the plunger.

er carried spots whenever the step-by-step movement of the rotor is discontinued.

27. A pad and spot assembling machine comprising a rotor having a plurality of faces each equipped with a set of pad feeding guideways therein and a set of plunger bores each centrally traversing one of the guideways, slide means normally closing the guideways of each set and disposed to center pads on the axes of the bores of the respective set, a set of suction plungers reciprocable in each set of bores, means for moving the rotor step-by-step to serially present the faces thereof, a loading station and means thereat for feeding pads to said sets of guideways, means for supporting fusible adhesive coated spot material at said station, means at said station including a set of punches for punching spots from said material and applying them for pneumatic attachment to the sets of plungers as they are serially presented, heating means disposed adjacent the periphery of the rotor, means for projecting the sets of plungers beyond the rotor periphery during a portion of the rotor travel to present the attached spots to the heating means, means for at a place subsequently reached withdrawing the plunger sets serially into their bores to permit the sets of pads to feed into centered relation against the slides and for then pressing the plunger sets against the pads and holding them there during a travel interval of the rotor to adhesively unite said pads and spots, and means for thereafter serially moving the slides to discharge the assembled pads.

28. In a pad and spot assembling machine a spot forming carrying and applying plunger having provision for pneumatically holding a spot thereon, spot material supporting means, a die, means for causing the die and the plunger to interengage with the spot material therebetween to form a spot, and means for withdrawing the plunger with the spot thereon and applying it to a pad.

29. In a pad and spot assembling machine a spot forming carrying and applying plunger having provision for pneumatically holding a spot thereon, spot material supporting means, a die, means for causing the die and the plunger to interengage with the spot material therebetween to form a spot, means for withdrawing the plunger with the spot thereon and applying it to a pad, and a yieldable stripper plunger opposing the suction plunger during the formation of the spot and operable to strip the spot from the die.

30. In a pad and spot assembling machine, a support having a pad feeding guideway therein and a plunger bore centrally traversing said guideway, a movable slide normally closing the guideway and disposed to center a pad on the axis of the bore, a die plate having a spot defining opening therein disposed adjacent and in axial alignment with the bore, means for supporting spot forming material across said opening, a suction plunger in said bore, and means for causing the plunger and the die opening to interengage to punch form a spot, means for withdrawing the plunger with the spot pneumatically affixed thereto across the guideway to permit a pad to be fed onto the slide, and means for projecting the plunger to apply the spot to a pad supported on said slide.

31. In a pad and spot assembling machine, a support having a pad feeding guideway therein and a plunger bore centrally traversing said guideway, a movable slide normally closing the

guideway and disposed to center a pad on the axis of the bore, a die plate having a spot defining opening therein disposed adjacent and in axial alignment with the bore, means for supporting heat fusible spot forming material across said opening, a suction plunger in said bore, and means for causing the plunger and the die opening to interengage to punch form a spot, heating means, means for presenting the suction plunger and the spot thereon to said heating means, means for withdrawing the plunger with the spot pneumatically affixed thereto across the guideway to permit a pad to be fed into the slide, and means for projecting the plunger to apply the spot to a pad supported on said slide.

32. In a pad and spot assembling machine, a support having a pad feeding guideway therein and a plunger bore centrally traversing said guideway, a movable slide normally closing the guideway and disposed to center a pad on the axis of the bore, a die plate having a spot defining opening therein disposed adjacent and in axial alignment with the bore, means for supporting heat fusible spot forming material across said opening, a suction plunger in said bore, and means for causing the plunger and the die opening to interengage to punch-form a spot, a yieldable stripper plunger opposing the suction plunger during the formation of the spot and operable to strip the spot from the die, means for withdrawing the plunger with the spot pneumatically affixed thereto across the guideway to permit a pad to be fed into the slide, and means for projecting the plunger to apply the spot to a pad supported on said slide.

33. In a pad and spot assembling machine, spot forming and applying means including a suction plunger for punching the spot, translating the spot to a place of assembly and there applying and pressing the spot in place upon a pad.

34. In a machine of the character described, a step-by-step rotatable table, means including a clutch for applying power to move the table, pad supporting and spot applying means including spot carrying plungers, heating means disposed adjacent the periphery of the table, means for projecting the plungers at the periphery of the table to present the spots to the heating means, and means operable upon disengagement of said clutch for rendering said heating means ineffective.

35. In closure cap spot forming and assembling apparatus, the combination of a die, a punch movable through the die, a carrier plunger disposed in opposed relation to the punch and adapted to directly receive a spot formed by the punch, and means for moving the plunger to engage the spot with a cap pad.

36. In closure cap spot forming and assembling apparatus, the combination of a die, a punch movable through the die, a carrier plunger disposed in opposed relation to the punch and adapted to directly receive a spot formed by the punch, a stripper plunger carried by the punch and effective upon withdrawal of the punch to strip the formed spot therefrom and press it against said plunger, and means for moving the carrier plunger to apply the spot to a cap pad.

37. In closure cap spot forming and assembling apparatus, the combination of a die, a punch movable through the die, a carrier plunger disposed in opposed relation to the punch and having a suction duct axially disposed therein and extending through the end thereof opposed to

the punch so as to adapt it to receive and pneumatically hold a spot formed by the punch, and means for moving the plunger to engage the spot with a cap pad.

5 38. In closure cap spot forming and assembling apparatus, the combination of a die, a punch movable through the die, a carrier plunger disposed in opposed relation to the punch and having a suction duct axially disposed therein and 10 extending through the end thereof opposed to the punch so as to adapt it to receive and pneumatically hold a spot formed by the punch, a stripper plunger disposed in a recess in and extending centrally endwise from said punch and 15 effective upon withdrawal of the punch to strip the formed spot therefrom and press it against said plunger, and means for moving the carrier plunger to apply the spot to a cap pad.

39. In closure cap spot forming and assembling 20 apparatus, the combination of a die, a punch movable through the die, a carrier plunger disposed in opposed relation to the punch and having a suction duct axially disposed therein and extending through the end thereof opposed 25 to the punch so as to adapt it to receive and pneumatically hold a spot formed by the punch, a stripper plunger disposed in a recess in and extending centrally endwise from said punch and 30 effective upon withdrawal of the punch to strip the formed spot therefrom and press it against said plunger, said stripper plunger being of a diameter in excess of the cross sectional area of 35 said suction duct whereby to prevent a breaking of the suction during the stripping of the spot

from the punch, and means for moving the carrier plunger to apply the spot to a cap pad.

40. In closure cap spot forming and assembling apparatus, the combination of a support having a battery of spot receiving openings therein, a 5 slide reciprocable toward and from said support and carrying a battery of punches aligned with said openings, and a die member carried by the slide and having bores therein for receiving and cooperating with the punches in the punch forming of spots, said die member and said punches being mounted for relative movement during reciprocation of the slide whereby in one direction of reciprocatory movement the die member will strike the support and the punches then move through said bores into said openings, and in the opposite direction of reciprocatory movement the punches will move out of said openings and clear said bores.

41. In closure cap spot forming and assembling 20 apparatus, the combination of a reciprocable slide having longitudinal guide bores therein, a battery of punches projecting longitudinally from said slide, rods slidable in and projecting through the respective ends of said guide bores, a die 25 member carried by said rods and having punch receiving openings therein, means for frictionally engaging the rods in the guide bores, and abutment means engageable by the rods and the die member in the respective directions of the reciprocatory movement of the slide for causing the die member and the plungers to move relatively 30 and the punches to alternately enter and withdraw from said die openings.

PAUL E. PEARSON. 35
